UNITED STATES PATENT OFFICE.

WILLIAM CARL MATTHEWS, OF PALATKA, FLORIDA.

LAMP FOR AUTOMOBILES.

Application filed September 19, 1925. Serial No. 57,309.

As is well known a very serious problem, which as far as I know has not been satisfactorily solved, is the provision of a lamp for automobiles which while giving adequate illumination or lighting of the road or street will not blind drivers of approaching automobiles. The object of my invention is to provide a lamp which will give all the necessary illumination of the roadway, but will not have the effect just stated above, and a further object is to provide such a lamp at the minimum cost without impairing its efficient action. A lamp embodying my invention is provided with reflecting surfaces of such form as will throw the light rays laterally of the direction of movement of the automobile, and at the same time so mask or cover the lighting element or member as to make impossible one approaching the automobile from in front seeing such lighting element. In what I consider now the most satisfactory embodiment of my invention, I provide two reflectors side by side each with a substantially semi-circular portion concentric with which the lighting element is placed and a tangentially extending portion, the two tangentially extending portions being side by side in a horizontal direction and extending obliquely in opposite directions which is longitudinally of the automobile or in the direction of travel thereof, these tangentially extending portions serving to reflect the light rays laterally and thereby illuminate the roadway at each side of the automobile. The reflecting surfaces preferably extend straight vertically, each reflector being formed of a flat strip bent into the shape just described. The reflectors and the lamp for each, preferably constitute a unit in addition to the ordinary headlight of the car upon which they may be mounted and a switch arrangement employed by which the headlight may be cut out of circuit and simultaneously the supplemental device cut into circuit and vice versa.

My invention consists in whatever is described by or is included within the terms or scope of the appended claims.

In the accompanying drawings:

Fig. 1 is a top plan view of the front portion of two approaching automobiles, each equipped with an illuminating device embodying my invention with the latter shown in horizontal section;

Fig. 2 is a side elevation of one of the automobiles;

Fig. 3 is a detail view in perspective of one of the reflectors.

Referring to Fig. 1 it will be seen that it is necessary to employ but one supplemental or auxiliary lamp embodying my invention, and it is located at the left side of the front of the automobile and comprises a suitable casing, 10, containing a light-giving element or member at front and rear which may consist of one electric lamp, 11, or more, say two and one above the other. For each of these light-giving members there is a reflector, 12, the two reflectors being placed side by side within the casing and of similar formation in that each comprises a substantially semi-circular end portion that extends concentrically around the lighting member, and a tangential portion that in the case of the forward lighting member extends obliquely rearward and outward, and in the case of the rear lighting member extends obliquely outward and forward, so that the reflecting surface in the case of the forward lighting member directs the rays of light to the left and rear of the automobile on the left side thereof, and in the case of the rear lighting member directs the rays of light to the right and forward. Inasmuch as the oblique reflecting surfaces are turned laterally and the lighting members are completely masked on the front side, it will be seen that to one in front of the automobile neither the lighting member or lamp, nor any reflecting surface is visible, and yet the roadway and other objects at both sides of the automobile are illuminated with all desired brilliancy. By reference to Fig. 1 which shows two automobiles approaching one another, it will be seen that each automobile by its lamp illuminates wholly by reflected light the roadway at the right and forward and the roadway at the left and rearward, and thus, by the two approaching cars the entire roadway is completely illuminated.

The obliquely extending tangential portion of each reflector may be straight or a parabola or other curve, it being only essential that the form and direction of the reflecting surfaces be such that the lamp or lighting members shall be completely masked to one directly in front, and that one directly in front shall not see any reflecting surface or any substantial part thereof.

Referring to Fig. 2 it will be seen that the casing, 10, is supported by its own arm or bracket, 13, from some part of the automo-

bile chassis and conveniently above the customary head lamp, 14, and preferably a switch arrangement, 16, is used by which when the head lamp light is cut off the lighting members of my lamp will be cut in circuit and vice versa.

The opposite sides of the casing are closed by glass plates, 15, which may be plain glass or otherwise.

- 10 It will be understood that if desired a single lamp structure may be employed that will house the customary headlight and my supplemental lighting device or the two may be made and sold as separate units and 15 separately installed. As to such matter as these, it is to be understood that I do not restrict the scope of my protection.

It will be understood that the entire surface of the reflector, 12, including both the 20 portion concentric with the lighting member and the tangential obliquely extending portion is a light-reflecting surface so that rays of light passing from the lighting element or member which reach such surface 25 are directed upon the roadway with the rays that are free from obstruction to direct transmission from the lighting member to the roadway. Thus by direct transmission and reflection the light emitted by the lighting element or member is transmitted to the 30 roadway. By "lighting element" or "lighting member", I mean one or any number of lamps.

What I claim is:

1. An automobile lamp comprising two 35 light emitting members mounted at the front of the automobile one in advance of the other, and a similar reflector for each member comprising a portion extending substantially halfway around the member and a 40 tangential obliquely extending portion, one obliquely extending portion extending rearward and the other obliquely extending portion extending forward, both light emitting members being masked by its reflector to one 45 directly ahead of the automobile, and all reflecting surfaces of both reflectors being masked to one directly in front of the automobile.

2. An automobile lamp comprising two 50 light-emitting members mounted at the front of the automobile one in advance of the other and reflecting surfaces situated between the two lamps, one extending obliquely forward from the rear lamp and terminating in advance and to one side thereof, and having a portion extending in rear of the lamp, and the other reflecting surface extending obliquely rearward from the front lamp and terminating in rear thereof, and at the front 55 extending around the front lamp, and all of such reflecting surfaces being masked to a person directly in front of the automobile.

In testimony whereof I hereunto affix my signature.

WILLIAM CARL MATTHEWS.
